UNITED STATES PATENT OFFICE.

MATTHEW GEORGE COKER, OF NEW YORK, N. Y.

DESIGN FOR A FLAG.

No. 39,541.

Specification for Design.

Patented Sept. 15, 1908.

Application filed May 21, 1908. Serial No. 434,197. Term of patent 7 years.

To all whom it may concern:

Be it known that I, MATTHEW GEORGE COKER, a citizen of the United States, residing in the borough of Brooklyn, in the city and State of New York, having invented a new, original, and ornamental Design of a Flag, of which the following is a specification, reference being had to the accompanying drawing, forming part thereof.

The figure is a face view of a flag showing my new design.

I claim

The ornamental design for a flag as shown.

M. GEORGE COKER.
